MOLDING PRESS

Arthur M. Howald, Toledo, Ohio, assignor, by
mesne assignments, to Plaskon Company, In-
corporated, a corporation of Delaware

Application June 11, 1935, Serial No. 26,085

8 Claims. (Cl. 60—52)

This invention relates to molding presses, and its principal object is to provide an electrically-operated hydraulic press having means for bringing the molding material quickly into engagement with the plunger of the mold and for thereafter moving the mold sections toward each other with uniform speed during flow of the molding material and, after the molding material has flowed to the shape of the mold, maintaining it under definite pressure for a definite time.

Other objects and advantages will be apparent from the following description, in which reference is had to the accompanying drawings illustrating a preferred embodiment of my invention and wherein similar reference numerals designate similar parts throughout the several views.

In the drawings:—

Figure I is a side elevational view of a molding press embodying my invention.

Figure II is an end elevational view of the molding press shown in Figure I.

Figure III is a partial plan view taken substantially along the line III—III of Figure I, a motor supporting frame and the parts carried thereby being removed and parts of the piping being broken away.

Figure IV is an enlarged fragmentary elevational view, partly in section, taken along the line IV—IV of Figure III.

Figure V is a wiring diagram showing circuits employed in controlling the operation of the molding press.

Figure VI is an enlarged sectional view showing the interior of a pump employed in the device of my invention.

Referring to the drawings in detail, the mechanism is mounted upon a box-like base 1 having a horizontal shelf-like extension 2 supporting a frame 3 upon which a reversible motor 4 is rigidly mounted. The motor 4 has a motor shaft 5 extending from both ends, and one end of the shaft 5 is connected to a speed reducer 6, the other end being connected, by means of a self-aligning collar 7, to a double acting, large capacity, low pressure oil pump 8. On the shelf-like extension 2 is bolted another speed reducer 9, which is driven from the speed reducer 6 by means of sprockets 10 and 11 and a roller chain 12, and is connected by means of a collar 13 to a shaft 14 (see Figure III).

Also bolted to the shelf-like extension 2 is a bracket 15 encasing a ball bearing 16 in which the shaft 14 is journaled, the shaft 14 being held by adjustable thrust collars 17 against endwise movement and being formed beyond the bearing

16 into a screw 18 (see Figures I and III). A high pressure ram 19 is rigidly mounted upon the shelf-like extension 2 by means of brackets 20. The ram 19 consists principally of a ram cylinder 22, having its interior bored and receiving a piston 21. The piston 21 has a short interiorly threaded portion at 22, the remainder of its interior being hollow and of sufficient diameter to freely receive the screw 18. Projections 24 on the ram cylinder and 25 on the bearing bracket 10 5 15 are rigidly connected by shouldered rods 26, and projections 27 on the piston are provided with openings to receive the rods 26 and slide thereon, the purpose of the rods 26 being to align and guide the piston and to prevent twisting movement from 15 being imparted by the screw to the piston. A packing gland 28 is mounted in the end of the ram cylinder 22 to prevent leakage of oil.

An intake pipe 29 leads from an oil reservoir (not shown) to the large capacity, low pressure pump 8. The pump 8 is of the gear type. When the gears are driven in the direction indicated by the slotted arrows in Figure VI the oil is drawn in through the intake pipe 29 and discharged through the piping 30. From one of the outlets of the pump 8, piping 30, in which is interposed a relief valve 31 connected to a return pipe 32, for a purpose which will be hereinafter explained, leads to a check valve 33, the check valve being connected to a side outlet T 34 by means of an elbow 35. One end of the side outlet T 34 is screwed into the opening at the discharge end of the ram cylinder 22. Another end of the T 34 is connected by means of a pipe 36 and a T 37 into an hydraulic press cylinder 38 (see Figure 35 IV).

The side outlet of the T 34 is connected to a contact pressure gauge 39 by means of a pipe 40. A pipe 41, leading from the T 37, is connected by means of an elbow 42 to a valve 43 operated by a solenoid 43, and there is also an outlet pipe 44 leading from the solenoid-operated valve 43 to the oil reservoir. The purpose of the solenoid-operated valve and the outlet pipe will be apparent when the description of the electrical control system is reached. The cylinder 38 is rigidly mounted upon the box-like base 1 by means of cap screws 45, and a plate 46 is welded in an annular under-cut portion 47 of the cylinder 38 to prevent leakage of oil. The inner wall of 50 the cylinder 38 is bored to receive an accurately machined piston 48. In the upper end of the cylinder 38 is machined an annular groove 49, within which packing and an adjustably mounted packing ring 50 are secured to prevent oil leak- 55

age and consequent pressure decrease. A movable table 51 is secured to the top of the piston 48 by means of cap screws and is provided with three guide sleeves 52, 53 and 54, which are adapted respectively to receive guide shafts 55, 56 and 57. The guide sleeves are provided with adjustable positioning rings 58 to insure proper location of the table 51. The guide shafts are threaded at their lower ends into a rigid member 59 lying within the box-like base 1 and engaging the inside of the top of the base directly under the cylinder 38, for the purpose of counteracting strains caused by downward pressure of the cylinder upon the base. The upper ends of the guide shafts 55, 56 and 57 are threaded and secured by nuts 60 and 61 to a stationary head 62.

Projections 63 on the movable table 51 carry ejector pistons 64 and slidably receive rods 65, the rods being bolted beneath the shelf-like extension 2 and rigidly supporting ejector or pull-back cylinders 66 and holding them from upward movement due to reactive force when pressure is applied to the ejector pistons. The ejector cylinders are provided with packing and adjustable packing rings 67 to prevent leakage of oil and loss of pressure. Piping 68 from the other outlet of the low pressure pump 8 leads to the top of the ejector cylinders, the piping 68 including a relief valve (not shown) identical in construction to the relief valve 31, but adjusted to open at lower pressure.

In molding certain materials, application of heat during the molding operation is necessary, and, therefore, I have provided pipes 69, with flexible tubes 70 and 71, which are connected into the molding block 72 and plunger 73 to supply any suitable heating fluid, preferably hot oil.

Referring to the wiring diagram (Figure V), current is supplied from the trunk line indicated by the numerals 74 and 75 to a switch 76, which, when closed, permits current to flow through a wire 78 and through a normally closed limit switch 79, and thence through a wire 80 to a normally open push-button starting switch 77. When the push-button starting switch 77 is closed, current can flow through a normally closed push-button stop switch 81 and through a wire 82 and the contacts of a normally closed relay 83 and energize the coil of a relay 84, thus causing the current to pass around the starting switch 77 and continue to flow through the wire 85 after the starting switch 77 is opened. The current flows through the normally closed contacts of the contact pressure gauge 39 and thence through the lead 86 to a normally closed limit switch 87. The limit switch 87 is only opened in case the piston 21 of the ram 19 moves forward to substantially its limit of movement, the limit switch 87 being interposed in the line to the motor 4 to stop the motor whenever the piston 21 reaches its limit of movement. This condition rarely occurs. From the limit switch 87 current passes to the forward winding 88 of the reversible motor 4, causing the motor to travel in a forward direction, thus operating the large capacity, low pressure pump 8 and the high pressure ram 19, forcing oil into the hydraulic press cylinder 38 and causing the piston 48 to rise rapidly until it encounters resistance because of engagement of the molding material with the plunger section of the mold, whereupon the relief valve 31 opens and the oil which is pumped by the large capacity, low pressure pump 8 is returned to the reservoir through the return pipe 32.

75 The ram 19 continues to force oil into the hy-

draulic press cylinder 38 and increase the pressure in the hydraulic press cylinder and in the contact pressure gauge 39. So long as the contacts of the contact pressure gauge 39 remain closed, current passing through the contacts, and then through a wire 86 to a wire 89, energizes the coil of a normally closed relay 90, thus preventing the flow of current through the relay. When pressure in the contact pressure gauge 39 has increased sufficiently to open the contacts of the contact pressure gauge, the forward winding of the motor is no longer energized and the motor stops. At the same time, the relay 90 is de-energized and current flows through a wire 91, the contacts of the relay 90, and a wire 92, 15 energizing the coil of a normally open relay 93. Thereafter current from the wire 85 goes through a wire 94, through the closed contacts of the relay 93, and thence through wires 95 and 96, and energizes the heating coil 97 of a thermostatically-controlled delayed-action relay 98. Although the motor is stopped, the pressure in the hydraulic press cylinder 38 and the contact pressure gauge 39 is maintained so long as the thermostatically-controlled delayed-action relay does not close and so long as the piston 48 of the hydraulic press does not yield and there is no leakage in the oil pressure system. The contact pressure gauge may be so adjusted that the contacts are opened at any predetermined pressure and in practice the gauge is so adjusted that the contacts are not opened until the molding material has flowed to the shape of the mold and the mold is closed, after which the piston 48 of the hydraulic press ceases to yield to the pressure of the oil. Current passing through the heating coil 97 of the thermostatically-controlled delayed-action relay 98 is sufficient to heat the thermostat but not sufficient to energize the relay 83. The thermostat may be adjusted to close the delayed-action relay after the predetermined interval during which it is desired that pressure be maintained upon the material in the mold.

When, after such predetermined interval, the thermostatically-controlled delayed-action relay 97 closes, the relay 83 is energized, breaking the circuit through its contacts and de-energizing the relay 84, thereby providing a path for current from a wire 100 to a wire 101 and the limit switch 99 (which was closed when the piston 21 started to move into the cylinder 23 of the ram 19). The current passing through the wire 101 and the closed limit switch 99 energizes the reverse winding 102 of the reversible motor 4, causing the motor and speed reducing mechanism to turn backwardly and the piston 21 to back out of the cylinder 23 of the hydraulic ram 19 until the contacts of the limit switch 99 are opened. At the same time current is supplied to the reverse winding 102 of the reversible motor 4, current is also supplied to the solenoid coil of the solenoid 43 operating the valve 43, which opens and permits oil to flow from the cylinder 38 of the hydraulic press back to the reservoir. The normally closed limit switch 79 is opened by the up-stroke of the solenoid-operated valve 43 and serves as a safety means to prevent current from passing to both the forward coil 88 and the reverse coil 102 of the reversing motor 4 at the same time, if the starting button 77 should be closed for the purpose of starting the device before the cycle is complete. When the piston 21 opens the contacts of the limit switch 99, the reverse winding of the motor 4 and the solenoid coil of the solenoid-operated valve 43 both are de-en-

ergized and the electrical system reassumes the condition in which it is shown diagrammatically in Figure V.

If prior to the closing of the thermostatically-controlled delayed-action relay 98 the pressure on the contact pressure gauge 39 should fall because of yielding of the hydraulic press piston 48 or because of oil leakage, the contacts of the contact pressure gauge would close the current again would flow through the wire 86 and the limit switch 87 to the forward winding of the reversible motor 4 and the pressure in the hydraulic press cylinder 38 would increase again until the contacts of the contact pressure gauge 39 again were opened. The thermostatic element 93 is so connected in the electrical system that closing and opening the contacts of the contact pressure gauge 39 caused by decreasing and increasing pressure will not affect the time of operation of the thermostatically-controlled delayed-action relay 98. The pressure in the hydraulic press cylinder 38 thus is maintained at approximately the point at which the contacts of the contact pressure gauge 39 are set to open even though the hydraulic press piston 48 may yield slightly or slight leakage of oil may take place.

The relays of the electrical control system are housed in a cabinet 103 which is mounted beneath the shelf-like extension 2 of the base. In the operation of the device, the proper quantity of molding compound is placed in the heated lower mold section 72 and the starting button 77 is pressed. The reversible motor 4 travels in a forward direction, driving the pump 3, which forces oil at a rapid rate into the cylinder 38. The motor at the same time drives the speed reducers 6 and 9, which, in turn, operate the screw 18, forcing the piston 21 slowly into the cylinder 23 of the high pressure ram 19, so that the high pressure ram also forces oil into the hydraulic press cylinder 38, but at a much slower rate. When the lower section 72 of the mold has risen into position in which the molding material is brought into engagement with the mold plunger 73 of the mold, the pressure in the hydraulic press cylinder 38 quickly rises to a point at which the relief valve 31 opens, and the oil passing through the pump is returned through the pipe 32 into the reservoir. The check valve 3 prevents escape of oil from the high pressure ram cylinder 23 and the hydraulic press cylinder 38 through the relief valve 31. Hence the piston continues to rise at greatly reduced speed as oil is forced from the cylinder 23 of the high pressure ram 19 into the hydraulic press cylinder 38, and the molding material is forced into the shape of the mold. The pressure in the hydraulic press cylinder is transmitted to the contact pressure gauge 39, and when the pressure has risen to the limit at which the contacts of the contact pressure gauge are set to open, the motor stops and heat is applied to the thermostatic element of the thermostatically-controlled delayed-action relay 98. If the piston 48 of the hydraulic press yields further before the contacts of the thermostatically-controlled delayed-action relay close, the motor again starts in a forward direction and the high pressure ram 19 forces additional oil into the hydraulic press cylinder 38, thus re-establishing the pressure and again causing the contacts of the contact pressure gauge 39 to open.

The molded material thus is held under predetermined pressure for a predetermined interval until the thermostatically-controlled delayed-action relay closes, whereupon the solenoid-actuated

valve 78 opens to allow oil from the hydraulic press cylinder 38 to flow back to the oil reservoir. The motor turns in reverse direction (as indicated by the broken arrows in Figure VI) to withdraw the piston 21 from the cylinder 23 of the high pressure ram 19 to pump oil through the pipe 88 to the ejector cylinders 66 and exert a downward push on the table 51 sufficient to open the mold and start the table downwardly, oil pumped in excess of the capacity of the ejector cylinders being returned to the reservoir through a relief valve (not shown). After the mold is broken apart the table will settle by its own weight as oil flows from the hydraulic press cylinder 38, but the pressure in the ejector cylinders 66 serves to overcome any tendency that the table may have to stick above its lowermost position.

After the starting switch 77 has closed, the series of operations takes place automatically. By adjusting the position of the contacts of the contact pressure gauge 39, any predetermined final pressure may be employed in the molding operation, and by adjusting the thermostatically-controlled delayed-action relay 98 the pressure may be maintained for any desired interval.

The embodiment of my invention herein shown and described is to be regarded as illustrative only, and it is to be understood that the invention is susceptible to variation, modification and change within the spirit and scope of the subjoined claims.

Having described my invention, I claim:

1. In a device of the class described, in combination, a hydraulic press cylinder, a piston movable therein, a high capacity pump for forcing liquid into said hydraulic press cylinder, a high pressure ram for also forcing liquid into said hydraulic press cylinder, means for separately and simultaneously operating said pump and ram, means operative upon the attainment of a comparatively low pressure for automatically causing liquid from said pump to cease to flow into said hydraulic press cylinder, means operative upon attainment of a higher pressure for automatically stopping the action of said high pressure ram, and means operative after a predetermined interval for automatically returning said high pressure ram to its initial condition.

2. In a device of the class described, in combination, a hydraulic press cylinder, a piston movable therein, a high capacity pump for forcing liquid into said hydraulic press cylinder, a high pressure ram for also forcing liquid into said hydraulic press cylinder, means operative upon the attainment of a comparatively low pressure for automatically causing liquid from said pump to cease to flow into said hydraulic press cylinder, means operative upon attainment of a higher pressure for automatically stopping the action of said high pressure ram, means operative after a predetermined interval for automatically returning said high pressure ram to its initial condition, and means operative also after said predetermined interval for automatically discharging liquid from said hydraulic press cylinder.

3. In a device of the class described, in combination, a hydraulic press cylinder, a piston movable therein, a high capacity pump for forcing liquid into said hydraulic press cylinder, a high pressure ram for also forcing liquid into said hydraulic press cylinder, means for separately and simultaneously operating said pump and ram, a relief valve operative upon the attainment of a comparatively low pressure for automatically

causing liquid from said pump to cease to flow into said hydraulic press cylinder, means operative upon attainment of a higher pressure for automatically stopping the action of said high pressure ram, and means operative after a predetermined interval for automatically returning said high pressure ram to its initial condition.

4. In a device of the class described, in combination, a hydraulic press cylinder, a piston movable therein, a high capacity pump for forcing liquid into said hydraulic press cylinder, a high pressure ram for also forcing liquid into said hydraulic press cylinder, a relief valve operative upon the attainment of a comparatively low pressure for automatically causing liquid from said pump to cease to flow into said hydraulic press cylinder, means operative upon attainment of a higher pressure for automatically stopping the action of said high pressure ram, means operative after a predetermined interval for automatically returning said high pressure ram to its initial condition, and means operative also after said predetermined interval for automatically discharging liquid from said hydraulic press cylinder.

5. In a device of the class described, in combination, a hydraulic press cylinder, a piston movable therein, a high capacity pump for forcing liquid into said hydraulic press cylinder, a high pressure ram for also forcing liquid into said hydraulic press cylinder, means for separately and simultaneously operating said pump and ram, means operative upon the attainment of a comparatively low pressure for automatically causing liquid from said pump to cease to flow into said hydraulic press cylinder, means operative upon attainment of a higher pressure for automatically stopping the action of said high pressure ram, and means operative after a predetermined interval for forcing the piston of said hydraulic press backwardly toward its initial position.

6. In a device of the class described, in combination, a hydraulic press cylinder, a piston movable therein, a high capacity pump for forcing liquid into said hydraulic press cylinder, a high pressure ram for also forcing liquid into said hydraulic press cylinder, a reversible motor for operating said pump and said ram, a relief valve for automatically discharging liquid from said

pump upon the attainment of a comparatively low pressure in said hydraulic press cylinder, means operative upon the attainment of a higher pressure in said hydraulic press cylinder for stopping said motor, and means automatically operative after a predetermined interval for causing said motor to rotate in reverse direction and back said ram.

7. In a device of the class described, in combination, a hydraulic press cylinder, a piston movable therein, a high capacity pump for forcing liquid into said hydraulic press cylinder, a high pressure ram for also forcing liquid into said hydraulic press cylinder, a reversible motor for operating said pump and said ram, a relief valve for automatically discharging liquid from said pump upon the attainment of a comparatively low pressure in said hydraulic press cylinder, means operative upon the attainment of a higher pressure in said hydraulic press cylinder for stopping said motor, means automatically operative after a predetermined interval for causing said motor to rotate in reverse direction and back said ram, and means automatically operable also after said predetermined interval for discharging the liquid from said hydraulic press cylinder.

8. In a device of the class described, in combination, a hydraulic press cylinder, a piston movable therein, a high capacity pump for forcing liquid into said hydraulic press cylinder, a high pressure ram for also forcing liquid into said hydraulic press cylinder, a reversible motor for operating said pump and said ram, a relief valve for automatically discharging liquid from said pump upon the attainment of a comparatively low pressure in said hydraulic press cylinder, means operative upon the attainment of a higher pressure in said hydraulic press cylinder for stopping said motor, means automatically operative after a predetermined interval for causing said motor to rotate in reverse direction, means automatically operable also after said predetermined interval for discharging the liquid from said hydraulic press cylinder, and means operative upon turning of said motor in reverse direction to force said piston toward its initial position in said hydraulic press cylinder.

ARTHUR M. HOWALD.
